UNITED STATES PATENT OFFICE.

WILLIAM H. KEWISH, OF PAINESVILLE, OHIO.

WRENCH.

Application filed May 7, 1924. Serial No. 711,576.

This invention relates to wrenches. More particularly it comprises wrenches of a type adapted to be quickly adjusted to the object to which they are applied and to be locked in 5 clamping relation therewith with a minimum of adjustment.

One difficulty with wrenches of this type is found to be the ease with which the adjusted position may be disturbed when the 10 wrench is intended to be used repeatedly upon the same size of object, and another disadvantage often found is that the clamping adjustment of the wrench is somewhat insecure and under certain conditions will 15 cause a release of the jaws because the moving parts were not completely engaged.

The object of the present invention is to provide a quickly adjustable wrench which will be free of the disadvantages referred to. 20 Other objects will appear in the course of the following description. To the accomplishment of the foregoing and related ends, said invention, then, consists of the means hereinafter fully described and particularly 25 pointed out in the claims.

The annexed drawings and the following description set forth in detail certain mechanism embodying the invention, such disclosed means constituting, however, but one of 30 various mechanical forms in which the principle of the invention may be used.

In said annexed drawings:—

Fig. 1 is a side elevation showing a wrench embodying the principle of the invention 35 with the adjusting worm thereof out of engagement with the rack teeth; Fig. 2 is a view similar to the view in Fig. 1 showing the jaw portion of the wrench with the adjusting worm engaged with the rack teeth; 40 Fig. 3 is a top plan view of the wrench as shown in Fig. 2; Fig. 4 is an enlarged longitudinal sectional view of the adjusting worm and its associated mechanism; and Fig. 5 is an end view of the adjusting worm showing 45 the cutting away of the threads upon one side.

While the principle of the invention may be embodied in other forms of construction, the device illustrated is that of the conventional form of monkey wrench having a shank portion 1, terminating in a handle portion 2 at one end and a fixed jaw portion 3 at the opposite end. The inner edge of the shank is provided with a series of teeth 55 forming a rack 4. A movable jaw 5 is sup-

ported upon a sleeve 6, preferably formed integrally therewith and adapted to slidably engage the shank of the body portion of the wrench. The movable jaw section of the wrench, immediately behind the movable jaw, is provided with a cutout portion 7 extending transversely thereof, said cutout portion extending to a point on a line with or a little beyond the base of the rack teeth when the same is engaged over the shank of 60 the wrench.

Upon one side of the cutout portion an inclined web 8 is provided which partially closes the cutout portion of the movable jaw section and provides a downwardly inclined 70 cam face 9 on its rearward edge for a purpose to be presently described. At each end of the cutout portion of the movable jaw a recess is provided through which a pin 11, 75 adapted to serve as a support for a worm 12, is secured by having its forward end 13 screw-threadedly engaged within the recess there provided. The worm is provided with a central longitudinal opening 14, to slidably engage the pin and is counterbored at its rearward end to provide a recess 15 to receive one end of a coiled spring 16, the other end of which abuts against the rearward inner face of the cutout portion of the movable jaw section of the wrench. The worm 80 is of somewhat less length than the space provided by the cutout portion in the movable section of the wrench, and thus a movement longitudinally of the pin when forced rearwardly against the spring is provided 85 for.

The outer surface of the worm is provided with screw-threads 17, which are interrupted along one longitudinal side to provide clearance of the worm above the outer ends of the 90 rack teeth, as is clearly shown in Fig. 1. The screw-threaded portion of the worm projects beyond the body portion thereof in line with the web on the movable jaw heretofore referred to, and the end face 18 of the interrupted screw-thread is adapted to abut against the cam face 9 of said web and to 95 coact therewith to force the worm rearwardly on the pin. When the worm is thus moved it will compress the spring 16 within the recess at its end, such movement being caused by turning the worm in a counter-clockwise direction. When thus turned the portion of the worm having the interrupted threads is brought immediately above the 100 105 110

rack teeth and the movable jaw is thus free to be shifted longitudinally of the shank to any desired position.

When the worm is turned in a clockwise direction, the pressure of the cam faces of the worm and the movable jaw is relieved. This rotation of the worm engages the screw-threads with the rack teeth and holds the worm against free movement. As soon as 10 the cam face 18 clears the cam face 9, the movable jaw is free to move rearwardly, and where a spring 16 of sufficient strength is employed, the forward inner face of the cut-out portion of the movable jaw will be 15 moved into contact with the forward end of the worm. Upon further rotation of the worm, clamping adjustment of the movable jaw toward the fixed jaw will be brought about. The construction is such, however, 20 that sufficient relative movement between the worm and the movable jaw is provided for so that the screw-threads of the worm will be adequately interengaged with the teeth of the rack before clamping action of the movable 25 jaw against the object to be engaged is brought about. Thus, there is no danger of the wrench slipping off the object after clamping adjustment is made, due to the insufficient engagement of the screw-threads 30 with the rack teeth. Likewise, where a loose fit upon the object operated upon is adequate and repeated adjustments to different faces of the same are necessary, the movable jaw may be maintained in the set position in 35 definitely, and the need for readjustment of the wrench after each application of the same to new faces of the object operated on will be avoided.

Other modes of applying the principle of 40 my invention may be employed instead of the one explained, change being made as regards the mechanism herein disclosed, provided the means stated by any of the following claims or the equivalent of such stated means be employed.

I therefore particularly point out and distinctly claim as my invention:—

1. A wrench having a shank, a jaw fixed to said shank, a series of rack teeth provided on 45 one side of said shank, a movable jaw en-

gaged for longitudinal movement on said shank for co-operation with said fixed jaw in engaging an object, a worm having screw-threads interrupted along a longitudinal line affording clearance from said rack teeth, a pin on said movable jaw for rotatably supporting said worm, and cam faces on said movable jaw and worm co-acting to shift said worm longitudinally of said pin when said worm is rotated out of engagement with 55 said rack teeth.

2. A wrench having a shank, a jaw fixed to said shank, a series of rack teeth provided on one side of said shank, a movable jaw engaged for longitudinal movement on said shank for co-operation with said fixed jaw in engaging an object, a worm having screw-threads interrupted along a longitudinal line affording clearance from said rack teeth, a pin on said movable jaw for rotatably supporting said worm, a coiled spring mounted on said pin between the rearward face of the worm and the adjacent face of the movable jaw, and cam faces on said movable jaw and worm co-acting with said spring to shift said worm longitudinally of said pin when said worm is rotated into and out of engagement with said rack teeth.

3. A wrench having a shank, a jaw fixed to said shank, a series of rack teeth provided on one side of said shank, a movable jaw engaged for longitudinal movement on said shank for co-operation with said fixed jaw in engaging an object, a worm having screw-threads interrupted along a longitudinal line affording clearance from said rack teeth, a pin on said movable jaw for rotatably supporting said worm, a coiled spring mounted on said pin between the rearward face of the worm and the adjacent face of the movable jaw, and cam faces on said movable jaw and worm adapted to move said worm rearwardly on said supporting pin against the tension of said spring when said worm is rotated in one direction and to permit said spring to move said jaw rearwardly against said worm when said worm is rotated in the reverse direction.

Signed by me, this 3 day of May, 1924.
WILLIAM H. KEWISH.
